(57) **CLAIM**

The ornamental design for a roof rack for utility terrain vehicle, as shown and described.

DESCRIPTION

FIG. 1 is a perspective view of a roof rack for a utility terrain vehicle showing the new design.

FIG. 2 is a front view of a roof rack for a utility terrain vehicle.

FIG. 3 is rear view of a roof rack for a utility terrain vehicle.

FIG. 4 is a first side view of a roof rack for a utility terrain vehicle.

FIG. 5 is a second side view of a roof rack for a utility terrain vehicle.

FIG. 6 is a top view of a roof rack for a utility terrain vehicle.

FIG. 7 is a bottom view of a roof rack for a utility terrain vehicle.

FIG. 8 is a perspective view of a roof rack for a utility terrain vehicle shown installed on the roof of a utility terrain vehicle in a fully extended position; and,

FIG. 9 is a perspective view of a roof rack for a utility terrain vehicle shown installed on the roof of a utility terrain vehicle in a fully collapsed position.

The broken lines in the drawings are for environment only and form no part of the claimed design.

1 Claim, 8 Drawing Sheets
